UNITED STATES PATENT OFFICE

2,308,330

HALF SHELF

George C. Harbison, Erie, Pa., assignor to General Electric Company, a corporation of New York

Application May 5, 1941, Serial No. 391,828

5 Claims. (Cl. 211—153)

My invention relates to refrigerator cabinets and the like, and more particularly to food supporting devices especially adapted for use in domestic refrigerators.

The objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawings in which Fig. 1 is a partial front elevational view of a refrigerator cabinet of the domestic type equipped with a shelf embodying the principles of my invention; Fig. 2 is an enlarged perspective view of a portion of the shelf shown in Fig. 1; Fig. 3 illustrates a modification of my invention; and Fig. 4 is an enlarged perspective view illustrating details of the arrangement of Fig. 3.

Referring to the drawings, I have shown a portion of a refrigerator cabinet 10 having suitable heat insulated walls defining a refrigerated storage compartment 11 adapted to be cooled by an evaporator or cooling element 12 shown in the upper portion of the food storage compartment. The access opening 13 to the storage compartment is closed by a suitable heat insulated door (not shown).

In the drawings there is illustrated a shelf 14 disposed in the upper portion of the food storage compartment between the side wall of the refrigerator and the cooling element. The particular shelf illustrated in the drawings comprises a marginal frame portion 15 and a plurality of longitudinally extending wires or bars 16 defining an article supporting surface or portion, the ends of the longitudinal members 16 being suitably secured to the front and rear portions of the frame 15, as by welding.

The shelf 14 is designed to be supported in one of a plurality of vertically spaced apart positions. In the illustrative form of my invention the shelf 14 is supportable in one of two positions. I have illustrated a pair of supporting devices at the rear portion of the shelf for supporting engagement with supporting members or elements as studs 17, for example, the studs being suitably supported on the rear wall of the food storage compartment. I have provided a pair of upwardly extending members 18 and 19 suitably secured as by welding for example, to the rear portion of the shelf frame. The upwardly extending members 18 and 19 may be formed in

any suitable manner. For example, the supporting members may be relatively flat, plate-like members provided with suitable apertures 20 and 21, respectively, for engagement with the studs 17 in the lower position of the shelf. Other forms of supporting members may be substituted, however. For example, the upwardly extending members 18 and 19 may take the form of upwardly extending wire loops suitably secured

10 as by soldering or welding to the shelf.

In order to support the rear portion of the shelf in the upper of the two selective positions, I have provided a downwardly extending member 22 of the same type as the upwardly extending members 18 and 19. The member 22 is also provided with an aperture for engagement with one of the supporting members or studs 17.

15 In the illustrative form of my invention the supporting member 22 is integral with the supporting member 19, the composite supporting member being formed by providing a plate-like member with two spaced apart apertures, the central portion of the member being fixedly secured to the rear frame portion of the shelf. It will be understood, however, that the upwardly and downwardly extending members may be secured in any desired position. The left rear portion of the shelf will rest on the left hand stud in the upper shelf position. The particular arrangement

20 illustrated is convenient because only two supporting elements or members, such as the studs 17, are required for supporting the rear portion of the shelf.

I have provided means for supporting the front portion of the shelf. This means is illustrated in the drawings as being carried by the evaporator or cooling element. However, the supporting means may be disposed within the food storage compartment in any desired position as from a side wall for example. I have provided a hanger 23 suitably secured to the side wall of the evaporator 12 as by means of a threaded fastening member or screw 24 extending through a suitable opening in the evaporator wall into

45 threaded engagement with a suitably tapped bore in the hanger or supporting member 23. The hanger is provided with a pair of spaced apart legs 25 and 26, the position of the legs corresponding with the vertical position provided at 50 the rear portion of the shelf. The legs or portions 25 and 26 are disposed in the form of laterally extending and then upwardly extending portions thereby providing hook-like portions for engagement with a laterally extending member 27 suitably secured as by welding for example,

to the frame 15 of the shelf. The supporting portion, or member 27, is in the form of an inverted L and is provided with a suitable opening or aperture 28 for receiving the upwardly extending portion of one of the hanger legs.

It will be seen that in the upper position of the shelf illustrated in Fig. 1, the shelf rests at the rear on the studs 17 extending outwardly from the rear wall of the food storage compartment, the loop 22 engaging one of the studs. 10 The front edge of the shelf is supported from the cooling element by means of the laterally extending portion 27 and the upper hook-shaped portion or leg 25 of the hanger or support 23. In the lower position of the shelf, the upwardly extending loops or members 18 and 19 engage the studs 17, and end portion 27 of the shelf engages the hook-shaped portion 26 of the adjacently disposed support 23.

I have provided releasable means for maintaining the shelf in position at all times, thereby preventing accidental blows from dislodging the shelf. In the form of my invention illustrated in the drawings this means takes the form of a relatively elongated resilient member or spring 29 suitably secured at one end thereof to the side portion of the frame 15 and projecting under the leg 25 or 26 depending upon the position of the shelf. It will be seen that the front portion of the member 29 effectively prevents the shelf from being raised sufficiently to be free of the upwardly extending portion of the leg engaging the shelf. In order to release or remove the shelf from its supported position the resilient member is moved sufficiently to the left, as viewed in Fig. 2, to permit the support 27 to pass upwardly out of engagement with the supporting leg. Thus, I have provided means which is normally disposed to prevent removal of the shelf and which may be moved to position permitting either removal from or application to the adjacent supporting means. The means for preventing accidental dislodgment of the shelf 14 may be applied to a shelf or supporting device which is not positionable in a plurality of vertical positions, as shown in Figs. 3 and 4. In these figures there is shown a different embodiment of the shelf retaining means shown in Figs. 1 and 2. The supporting means 23a comprises a pair of vertically spaced-apart laterally extending flanges 27a and 27b. The upper flange is apertured as indicated by the numeral 28a. The lower flange is arranged to be disposed on the underside of the hook-like portion 25a of the supporting member 23a in the shelf engaging position. In this form of my invention the shelf will be applied to or removed from its supporting members by tilting or rotating the shelf about the hook-like portion 25a a sufficient distance to permit the lower flange 27a to move past the hook-like portion 25a. Of course, in the arrangement in which the shelf will be disposed but in one position, only one hook-engaging portion will be necessary. As best seen in Fig. 3, one rear corner of the shelf is supported on a stud 17 and the other rear corner is carried from a second stud 17 by means of a supporting member or loop 19, suitably secured to the shelf 14.

Modifications will occur to those skilled in the art. Accordingly, while I have shown a particular embodiment of my invention I do not desire my invention to be limited to the particular construction shown and described and I intend in the appended claims to cover all modi-

fications within the spirit and scope of my invention.

What I claim as new and desire to secure by Letters Patent of the United States is:

5 1. A removable shelf comprising a marginal frame portion and an article supporting portion, means for supporting said shelf, said supporting means including a laterally extending element carried by said shelf, said element having an aperture therethrough, supporting means adjacent said shelf and having a lateral portion and an upwardly directed portion, said upwardly directed portion extending into said aperture, said laterally extending element resting on the lateral 10 portion of said supporting means, and means normally preventing vertical upward movement of said shelf including a member mounted on said shelf and extending under said lateral portion when said shelf is in the article-supporting position.

20 2. A removable shelf comprising marginal frame portions and an article supporting portion, a plurality of supporting members adjacent the rear portion of said shelf, the rear portion of said frame being provided with a pair of upwardly extending horizontally spaced apart members for engaging at least two of said supporting members in the lower position of said shelf, and a downwardly extending member for 25 engaging one of said supporting members in the upper position of said shelf, means for supporting the front portion of said shelf in a plurality of positions corresponding to the two aforementioned positions, said last mentioned means comprising a supporting member adjacent said shelf and having a plurality of vertically spaced apart shelf engaging portions.

30 3. A removable shelf comprising a marginal frame portion and an article supporting portion, means for supporting the rear portion of said shelf in a plurality of vertically spaced apart positions, said means comprising a plurality of supporting members adjacent the rear portion of said shelf, said rear frame portion having a pair of upwardly extending members for engaging at least two of said supporting members in the lower position of said shelf and a downwardly extending member for engaging with one of said supporting members in the upper position of said shelf, and means for supporting the front portion of said shelf in a plurality of positions corresponding to the first mentioned positions, means comprising a laterally extending element carried by said shelf, said element having an aperture therethrough, and a supporting member adjacent said shelf and having a plurality of hook-like portions extending laterally thereof for engagement with said aperture.

40 4. A removable shelf comprising a marginal frame portion and an article supporting portion, means for supporting the rear portion of said shelf in a plurality of vertically spaced apart positions, said means comprising a plurality of supporting members adjacent the rear portion of said shelf, said rear frame portion having a pair of upwardly extending members for engaging at least two of said supporting members in the lower position of said shelf and a downwardly extending member for engaging with one of said supporting members in the upper position of said shelf, and means for supporting the front portion of said shelf in a plurality of positions corresponding to the first mentioned positions, means comprising a laterally extending element carried by said shelf, said element having an aperture therethrough, and a supporting member adjacent said shelf and having a plurality of hook-like portions extending laterally thereof for engagement with said aperture.

45 5. A removable shelf comprising a marginal frame portion and an article supporting portion, means for supporting the rear portion of said shelf in a plurality of vertically spaced apart positions, said means comprising a plurality of supporting members adjacent the rear portion of said shelf, said rear frame portion having a pair of upwardly extending members for engaging at least two of said supporting members in the lower position of said shelf and a downwardly extending member for engaging with one of said supporting members in the upper position of said shelf, and means for supporting the front portion of said shelf in a plurality of positions corresponding to the first mentioned positions, means comprising a laterally extending element carried by said shelf, said element having an

aperture therethrough, a supporting member adjacent said shelf and having a plurality of hook-like portions extending laterally thereof for engagement with said aperture, and means for maintaining said shelf in engagement with said supporting member.

5. A removable shelf comprising a marginal frame portion and an article-supporting portion, means for supporting the rear portion of said shelf, means for supporting the front portion of said shelf, the last-mentioned means comprising a lateral extension on said shelf and a supporting member adjacent said shelf, said lateral extension having an aperture therethrough, said

10 member having a lateral portion extending under said extension, and an upwardly directed portion extending into said aperture, means for retaining normally said extension against vertical movement with respect to said supporting member, said last-mentioned means comprising a resilient member carried by said frame portion and normally disposed below said lateral portion but arranged to be moved to a position permitting said shelf to be removed from or placed in the article supporting position, and means for normally retaining said shelf against outward movement.

GEORGE C. HARBISON.
